DESIGN FOR A TANK BODY FOR VEHICLES

Joseph M. Kramer, Ward M. Gadberry, and Alonzo J. McElvain, Kansas City, Mo., assignors to Andrew A. Kramer, Kansas City, Mo.

Application August 24, 1935, Serial No. 58,287

Term of patent 14 years

To all whom it may concern:

Be it known that we, Joseph M. Kramer, Ward M. Gadberry, and Alonzo J. McElvain, citizens of the United States, residing at Kansas City, in the county of Jackson and State of Missouri, have invented a new, original, and ornamental Design for a Tank Body for Vehicles, of which the following is a specification, reference being had to the accompanying drawing, forming a part thereof. The figure is a perspective view of our new design.

The side of the tank body opposite that shown

corresponds in design to that side shown in the drawing. The front end thereof lies substantially in a vertical plane.

We claim:

The ornamental design for a tank body for vehicles substantially as shown and described.

In testimony whereof we hereunto subscribe our names this 12th day of August, 1935.

JOSEPH M. KRAMER.
WARD M. GADBERRY.
ALONZO J. McELVAIN.
